UNITED STATES PATENT OFFICE

FRANK J. SPRAGUE, OF NEW YORK, N. Y.

APPARATUS FOR CONTROLLING THE MOVEMENT OF VEHICLES ON RAILROADS

Original application filed April 12, 1927, Serial No. 183,193. Divided and this application filed July 6, 1929. Serial No. 376,399.

This application is filed as a division of my prior application, Ser. No. 183,193 of April 12, 1927, for apparatus for controlling movement of vehicles on railroads, and the subject hereof forms part of the apparatus disclosed in the aforesaid application.

My invention relates to an improvement in automatic train control systems, and particularly to the features known as forestalling and resetting, the former being an operation by which the engineer may, by the performance of a suitable manual act, prevent the coming on of an automatic brake application, and the latter an operation by which 15 the brake controlling apparatus may be restored to normal condition, after which the brakes (if applied) may be released and free running conditions established.

In much of present practice the forestalling and resetting operations are effected by mechanisms differently placed, the forestalling being done in the cab, and the resetting through a switch or other device situated at such inconvenient point as will require the 20 train to be stopped before it can be used, so as to prevent release of the brakes, applied in response to a track initiated impulse, before the train has come to rest, although sometimes this reset switch is made inconvenient but possibly accessible when moving at slow speeds.

To place some restriction upon the act of forestalling, which unless limited by the condition that a train must be actually braked 25 or has had its speed reduced to some predetermined rate—although present practice and rules actually permit forestalling at any speed and without any pre-application of the brakes—it has been proposed to limit the 30 time period in which the engineer may forestall an automatic brake application when receiving a track impulse. This is done in certain electrically controlled systems by connecting a forestalling switch and circuits so 35 that after manual operation of the switch by the engineer the forestalling circuit will be closed, and the essential circuit will be maintained for only a limited time, the movement of the switch handle initiating a motive force 40 which after a short interval will open the

essential circuit, just as the pilot circuits are made and opened in my Letters Patent No. 660,065 on the multiple-unit system of train control.

With this arrangement, the engineer, on approaching a stop indication point within a distance less than he will cover in a predetermined time, which may be anything from a hundred to a thousand feet or more, according to the speed of a train, moves his switch 55 to the forestalling position, closes the forestalling circuit and initiates the motive force, which will open the essential circuit automatically in a predetermined time—say 15 seconds. After passing the stop indication 60 point, if he returns the switch to the normal position within the time period there will be no automatic braking, although some part of the equipment may be responsive. But if the switch is held in the forestalling position for 65 longer than the time period the brakes will come on.

Thus there are three conditions in which the automatic brake application may take 70 place as a result of passing a stop indication point. First, if the engineer does nothing; second, if he forestalls too soon; and, finally, if he holds on too long. Any of these conditions may possibly act adversely as regards 75 train movements.

With the automatic brake application in effect, the amount of braking is made such as to bring the train to a stop, after which the engineer or fireman must get down from the cab, or climb out to a position difficult of access when the locomotive is moving, to reset the brake initiating apparatus, so that the engineer may release the brakes manually.

The main object of thus separating the forestalling and resetting actions, and providing for a time limit is to induce some measure of alertness on the part of the engineer, under possible penalty, and to insure that once the brakes have actually come on automatically the train shall be stopped before the engineer can release them.

There are serious objections to both practices and specifically to the lack of restriction of the use of a forestalling device, as well as to the necessity for getting out of the cab to 100

enable the brakes to be released. This latter act cannot be performed at times without serious danger, as in tunnels, snow-sheds and on trestles, or in proximity to passing trains and under conditions of poor visibility.

I desire, therefore, to provide definite limitations upon the act of forestalling, as well as upon the act of resetting, while the timing mechanism for opening the forestalling circuit may be omitted entirely. I plan, also, to combine in a single mechanism—operated in the cab—both the forestalling and resetting operations, and for compelling, under possible penalty, acknowledgment of the receipt of a brake initiating impulse from the track. This mechanism may conveniently be referred to as an "acknowledging device."

My invention will conduce to safety and convenience, and eliminate delays, while making it possible to impose upon the engineer such precautionary conditions as are essential to safe operation and the maintenance of the fundamentals of automatic train control systems.

The accompanying drawings and specification illustrate my invention as applied to a system of automatic train control which cooperates with the usual type of air brake equipment in whole or in part. It is of course applicable not only to vehicles propelled by steam but to vehicles otherwise propelled. It should be noted that the mechanic, electric and pneumatic devices shown in these drawings serve merely to illustrate the nature of the invention, and thus do not limit it to the construction shown.

In the accompanying drawing which forms part of this application—

Figure 1 is a diagrammatic illustration of the electric circuits of the vehicle-carried equipment of a train control system which incorporates my invention, also indicating in a schematic way the cooperating track elements.

Relay R represents the governing element of the circuits. This relay is normally energized, its maintaining circuit being the following: plus of battery H, armature A, contacts 7, 6, armature 2, and coil of relay R, and back to the negative of the battery. As the maintaining circuit of relay R includes its own armature 2 it is a "stick relay" which, when once de-energized, cannot be re-energized by way of its normal maintaining circuit.

The armature A represents an element for changing the electrical condition of the governing element of the circuits, which element is herein illustrated as a stick relay. The armature A is for convenience illustrated as biased by a spring 18 and is intended to be controlled by track elements. In the specific illustration it is normally held by its spring against its cooperating contact so as to close the maintaining circuit of relay R. How-

ever, if an active application track element is passed this armature A is so affected as to open the maintaining circuit of relay R at contact 7. The word "active" in this connection refers to the condition of the track element which is intended to initiate automatic braking and does not refer to the inherent condition of the track element itself. The term "track element" is likewise employed in its broadest sense irrespective of the type of system, whether continuous or intermittent, to which my invention is applied.

For illustrative purposes I have indicated in a schematic way an intermittent inductive type of system, such being fully described in my British Patent No. 149,922, or my United States Patent No. 1,669,165 of May 8, 1928. The track element is represented by an application magnet of the compound type which consists of a permanent magnet m provided with soft iron poles m' m' surrounded by neutralizing coils n—n. The neutralizing coils n are energized from a battery 150 for clear traffic conditions in which case their field neutralizes or deflects the field of the permanent magnet. For restricted traffic conditions, however, the neutralizing coils are de-energized in which case the flux of the permanent magnet is effective and the track element "active". The traffic control is shown in a conventional way. The receiver of the locomotive is represented by plates p which collect the flux when passing over an active magnet, whereby the armature A is magnetically attracted by the plates p and breaks the circuit of which it forms part.

The stick relay R normally maintains an armature 1 against a contact 4 in the normally closed circuit of an electro-pneumatic vent valve V.

The vent valve represents the connecting member between the electric and pneumatic parts of the vehicle-carried equipment, de-energization of which member initiates an automatic brake application. Various pneumatic equipment may be used in connection with my invention—for instance, the one described in my previously referred to application, Ser. No. 183,193 of April 12, 1927.

The circuit for V process through the plus end of battery H, and speed controlled contacts 130 and 131—which are normally electrically connected by a cylindrical contact 133—, to contact 14, contact 123 and contact 15 of an acknowledging device, F²; through coil 20 of the vent valve, front contact 4 and armature 1 of relay R, back to the negative end of battery H. The contact 123 of the acknowledging device F² is normally held by a spring 124 in its upper position so as to bridge contacts 14 and 15 and the speed controlled contacts are also electrically connected through contact 133—provided the speed of the train does not exceed a predetermined

maximum value. The circuit of the coil 20 is thus normally closed and the vent valve energized.

As mentioned previously, when the stick relay R is de-energized, as happens when passing over an active application track element, it cannot be re-energized by way of its normal maintaining circuit, even after such track element is passed and armature A has assumed its normal position; such re-energization can only take place by way of re-energizing circuits. These circuits which comprise contacts of a manually operated acknowledging device, as well as speed controlled and inertia controlled contacts will now be described.

The acknowledging device F³ here illustrated comprises the contact 123, which, as already stated, due to the action of spring 124, normally bridges the contacts 14 and 15. Upon manual actuation of the acknowledging device electric connection between the upper contacts 14 and 15 is broken and connection between the lower contacts 12 and 13 is established.

The speed contacts are controlled by a centrifugal speed governor M, which is provided with a battery brush 130, always connected with the positive end of the battery H, with a high-speed brush 131, and a low-speed brush 132. A rotating contact cylinder 133 electrically connects brushes 130 and 131 unless the train exceeds a high or maximum speed limit, which may be of the order of 50 to 70 M. P. H.; the electrical connection between the battery brush 130 and the low speed brush 132 is only maintained provided the speed of the train is below a so-called low speed limit which may be of the order of 10 to 20 M. P. H.; the values given being only for the purpose of illustration.

The pendulum device P comprises a weight 125 adjustably supported on a pendulum arm 127 which latter is normally retained against a contact 10' by an adjustable spring 126. The pendulum arm is of conductive material and is connected with the positive pole of battery H. This pendulum gives a measure of the rate and consequently of the amount of braking required to break the contact 10' and to make a contact 9', matters for determination by suitable adjustment to suit the requirements of the road adopting the system. The suggestion is made for the purpose of illustration that contact 10' be broken at the commencement of automatic braking and that contact 9' be made on full service braking.

There are three re-energizing circuits for the relay R, all of which go through the back contacts 12 and 13 of the acknowledging device F³.

Of these three circuits the one is the fore-stalling circuit which goes from plus battery through pendulum arm 127, pendulum con-

tact 10' to the acknowledging device contact 13 and, if the acknowledging device is manually depressed, through contact 123 and contact 13 thereof to the relay R and negative battery, thereby closing the relay circuit and re-energizing relay R. It should be noted that this circuit is only closed if the pendulum arm is in its normal position that is, before a retardation of the train due to an automatic braking has started. Thus, to forestall an automatic brake application the engineer has to close the acknowledging device before the automatic brake application has taken place.

The second re-energizing circuit is the reset circuit which is closed if the braking exceeds a certain rate—thus if a certain amount of braking has taken place—and the pendulum arm 127 contacts with contact 9'. By manually depressing the acknowledging device the reset circuit is closed as follows: plus battery, pendulum arm 127, pendulum contact 9', contact 12, contact 123 and contact 13 of the acknowledging device, relay R and back to negative battery.

The third re-energizing circuit goes through the low-speed contact 132 of the speed governor and is closed upon operation of the acknowledging device F³, provided the speed of the train is below the low-speed limit. This re-energizing circuit can be traced as follows: plus battery, speed contact 130, contact segment 133, speed contact 132, contact 12, armature 123 and contact 13 of the acknowledging device, relay R back to negative battery.

A warning device, audible, visible or both and represented in the drawing by the audible signal K, is provided. This alarm is energized whenever the relay R is de-energized as dropping of armature 1 closes the circuit of alarm K as follows:

Plus battery, audible signal K, contact 5, armature 1 and back to negative battery.

It should also be noted that a time delay should be provided between the de-energizing of the vent valve and the automatic application of the brake. This time delay may be varied from the fraction of a second to several seconds, depending on the requirements. There are many known ways of introducing such a time delay between the de-energization of the vent valve and the application of the brakes, for instance, the one described in my above-referred to application #183,193 of April 12, 1927.

Under normal conditions the stick relay is energized and its armatures 1 and 2 are attracted. The acknowledging device F³ is contacting with its contact 123 with the contacts 14 and 15. The speed contact 131—unless the speed exceeds the maximum speed limit—is connected with the brush 130 through K contact ring 133 and thus the coil 20 of the vent valve is energized. If the

train exceeds the maximum speed limit the vent valve is de-energized with a consequent application of the brakes. However, as soon as the train reduces its speed below the maximum speed limit the vent valve is automatically re-energized—the relay R not having been de-energized—and the brakes can be released.

However, when an active application impulse is received from the track, armature A is attracted, as previously described, thus breaking the circuit of stick relay R. De-energization of stick relay R causes armatures 1 and 2 to drop. This in its turn de-energizes the coil 20 of the vent valve and automatic brake application takes place unless proper action is taken by the engineer as hereinafter set forth.

When armature 1 drops it makes back contact 5 and closes the circuit of the audible signal K, which gives warning to the engineer of the danger conditions ahead, and that an automatic brake application will be effected unless forestalling action is taken by him.

Assume now that the engineer is not prepared to heed such warning or is incapacitated, an automatic brake application will then occur.

However, if the engineer is alert and wishes to take advantage of the forestalling privilege upon the receipt of the warning given by the audible signal K, he will move the acknowledging device F³ into its operating position and immediately release it thereafter. This first breaks the circuit of the coil 20 of the vent valve at contacts 14 and 15 and bridges the forestalling circuit of the relay R at contacts 12 and 13, provided that the forestalling contact 10' is closed by the pendulum arm 127 or that the low speed brush 132 is contacting with the cylinder segment 133. The first condition assumes that retardation due to automatic braking has not yet started and the second condition assumes that the train is below the low-speed limit. Releasing of the acknowledging device by the engineer returns contact 123 to the upper contacts 14 and 15, and as in the meantime the relay R has been re-energized the whole equipment is restored to normal condition.

It has been stated above, that there is a time delay provided between de-energization of the vent valve and the automatic application of the brake, also that after a track element is passed, armature A assumes its normal closed position. Thus it will appear that when contact 123, after having completed the forestalling circuit, is released and again bridges the upper contacts 14 and 15, normal condition of the equipment is restored without an automatic brake application taking place.

If, on the other hand, the engineer fails to forestall the automatic brake application,

he may re-energize relay R through the reset circuit by operating the acknowledging device, after sufficient retardation of the train has taken place to bring the pendulum arm 27 into contact with contact 9'. After re-energizing relay R the equipment can be restored to normal by releasing the acknowledging device.

As illustrated in the drawing, both the forestalling and the resetting can be effected irrespective of the position of the pendulum contacts (and thus of the retardation of the train) provided the train is below the low-speed limit. It should be understood, however, that my invention does not necessarily require the use of the low-speed contact. In the same way the maximum-speed contact may also be omitted.

Various modifications both in regard to the circuits as well as the physical embodiment of the devices may be employed without deviating from the spirit of the invention, and no undue limitation should therefore be deduced from the specific illustration given, but the appended claims should be construed as broadly as possible in view of the prior art.

What I claim as new and desire to secure by Letters Patent is:

1. In an automatic train control system of the permissive type, brake-setting apparatus, a combined forestalling and resetting device, and two pendulum-controlled contactors, said forestalling and resetting device permitting, by its identical manual operation, prevention of an automatic application of the brakes when operated prior to such application provided one of the pendulum-controlled contactors is closed, and restoration of the apparatus to normal in case an automatic application of the brakes has already been started provided that the other pendulum-controlled contactor is closed.

2. In an automatic train control system of the permissive type, brake-setting apparatus, a device to detect deceleration and contacts closed by said device, an acknowledging mechanism permitting, by identical manual operation, prevention of an automatic application of the brakes when operated prior to such application provided that one of the contacts of the device to detect deceleration is closed, and restoration of the apparatus to normal after an automatic application of the brakes provided that another contact of said device is closed.

3. In a system for automatically controlling a train, train carried equipment comprising brake-applying means, a combined forestalling and resetting device, said device permitting, by identical manual operation, prevention of an automatic application of the brakes provided no deceleration of the train exceeding a certain rate has occurred,

and the release of an automatic application provided the deceleration of the train has attained a predetermined rate.

4. In an automatic train control system comprising a normally active relay de-energized when a receiver on the locomotive registers inductively to form a magnetic couple with a traffic controlled element, a brake initiating circuit controlled thereby, and a restoring circuit for said relay including a manually operated switch normally retracted from the operating position and controlling normally open contacts in series with inertia controlled contacts.

5. In an automatic train control system comprising a normally active relay deenergized when a receiver on the locomotive registers inductively to form a magnetic couple with a traffic controlled element, a brake initiating circuit controlled thereby, and a restoring circuit for said relay including a manually operated switch normally retracted from the operating position and controlling normally open contacts in series with inertia controlled contacts paralleled by speed controlled contacts.

6. In an automatic train control system comprising a normally active relay de-energized when a receiver on the locomotive registers inductively to form a magnetic couple with a traffic controlled element, a brake initiating circuit controlled thereby, a restoring circuit for said relay including a manually operated switch normally retracted from the operating position and controlling normally open contacts in series with inertia controlled contacts and means for opening the brake initiating circuit when the restoring circuit is closed.

7. In a automatic train control system comprising a normally active relay de-energized when a receiver on the locomotive registers inductively to form a magnetic couple with a traffic controlled element, a brake initiating circuit controlled thereby, a restoring circuit for said relay including a manually operated switch normally retracted from the operating position and controlling normally open contacts in series with inertia controlled contacts paralleled by speed controlled contacts, and means for opening the brake initiating circuit when the restoring circuit is closed.

8. In an automatic train control system comprising a normally active relay de-energized when a receiver on the locomotive registers inductively to form a magnetic couple with a traffic controlled element, a brake initiating circuit controlled thereby, and a restoring circuit for said relay including a manually operated switch normally retracted from the operating position and controlling normally open contacts in series with inertia controlled contacts, said initiating cir-

cuit comprising contacts bridged by said switch when in normal position.

9. In an automatic train control system comprising a normally active relay de-energized when a receiver on the locomotive registers inductively to form a magnetic couple with a traffic controlled element, a brake initiating circuit controlled thereby, and a restoring circuit for said relay including a manually operated switch normally retracted from the operating position and controlling normally open contacts in series with inertia controlled contacts paralleled by speed controlled contacts, said initiating circuit comprising contacts bridged by said switch when in normal position.
